[57] **CLAIM**

An ornamental design for a cruciform center pivot, as shown.

DESCRIPTION

FIG. 1 is a top perspective view of a cruciform center pivot according to the invention.

FIG. 2 is a top plan view thereof.

FIG. 3 is a bottom plan view thereof.

FIG. 4 is an end view thereof, the opposing end view being identical; and,

FIG. 5 is a side view thereof, the opposing side view being identical.

The broken line portions of the figures are for illustrative purposes only and form no part of the claimed design.
